DIMPLING MACHINE

Edmund P. Wilson, Forty Fort, Pa., assignor to
American Chain & Cable Company, Inc., New
York, N. Y., a corporation of New York

Application December 21, 1939, Serial No. 310,366

12 Claims. (Cl. 140—113)

This invention relates to an apparatus for anchoring to stranded wire structures and the like attachments of various kinds either on the end or at any point on the length of said structures, or for connecting two such structures together, by indenting the exterior of such attachments.

In the patent to Conner #1,643,150 of September 20, 1927, a method is disclosed for securing a plain cylindrical fitting on to a stranded wire structure to develop the full strength of the stranded wire structure. In methods of this character the entire fitting is swaged so as to reduce its external and internal diameters to constrict the fitting on the stranded wire structure. When the stranded wire structure consists of steel wires the sleeve which is converted into an attachment preferably consists of softer steel which however must have sufficient thickness and rigidity to develop the full strength of the structure. These methods can be carried out only in the factory by means of heavy and expensive machinery.

It is therefore one object of my invention to provide a portable apparatus for securing such attachments on to stranded wire structures in the field and in order that this may be done, I have provided an apparatus for securing an attachment to a stranded wire structure in accordance with the means and method disclosed in a co-pending application Ser. No. 203,622 filed April 22, 1938, in which the sleeve or attachment is held on the wire structure by projections on the inner surface of the sleeve produced by indentations in the outer surface of the sleeve, such projections deforming the cross sectional shape of the sleeve and stranded wire structure and into non-circular and triangular form when there are three indentations in a transverse row, etc., such deformed cross sectional areas being orientated with respect to each other and the indentations of adjacent rows being staggered.

Other objects of the invention consist in providing an apparatus in which provision is made for connecting attachments of different diameters to stranded wire structures of different diameters, to provide means for indexing the sleeve with respect to the dimpling members and to provide means for preventing bending of the sleeve as it is being secured to the stranded wire structure.

Other objects of the invention will appear from the following description taken in connection with the drawings, in which—

Fig. 1 is a front elevational view of the apparatus showing parts in vertical section;

Fig. 2 is a vertical transverse section on the line 2—2 of Fig. 1;

Fig. 3 is a vertical longitudinal section on the line 3—3 of Fig. 2;

Fig. 4 is a vertical transverse section on the line 4—4 of Fig. 1; and

Fig. 5 is a perspective view of one form of end fitting connected to a cable by means of the apparatus disclosed.

- 10 The apparatus disclosed includes a frame comprising an elongated rectangular base member 10 and an upwardly extending triangular plate 11 which may be located on one side of the longitudinal center line of the base 10 to prevent the apparatus from being tilted to the left, Fig. 2, when pressure is applied on the operating ratchet lever 12 located on the other side of the longitudinal center line of the base.
- 15 Journaled in the plate 11 are shafts 13 and 14 which constitute the operating shafts of the apparatus. The shaft 13 is provided with a cylindrical bearing portion 15 journaled in the plate 11 and an adjacent cylindrical portion 16 to which is keyed a gear 17, a bearing washer 18 and nut 19 threaded on the shaft being provided to hold the gear 17 in position on the shaft and against one side of the plate 11 and to hold the shaft in position on the plate by drawing a collar 20 on the shaft against the opposite side of the plate 11 as is apparent from Fig. 2. The other end of the shaft 13 is squared at 22 to receive a rotatable dimpling wheel 23 and a ratchet drum 24 which are held in position against the collar 20 by a washer 25 and screw bolt 26 threaded in the end of the shaft 13. Cooperating with the ratchet drum 24 is a ratchet plunger pawl 28 pressed into engagement with the teeth of the ratchet drum by a spring 29 operating between a shoulder on the ratchet pawl 28 and the inner end of the manipulating portion 30 of the handle 12 which is threaded in the housing 31 of the pawl rotatably mounted on cylindrical shoulders 32 of the ratchet drum 24. The manipulating portion 30 of the handle is hollow 35 through which extends the stem 35 of the ratchet pawl 28, the upper end of which is equipped with a knurled head 36 by means of which the pawl may be withdrawn from the ratchet drum. Extending through the head 36 is a pin 37 which 40 is seated in a groove 38 in the outer end of the handle portion 39 to hold the ratchet pawl in proper working position. The pawl may be withdrawn from the ratchet drum and rotated and held in such position by the pin 37 bearing on the end of the manipulating portion 30.

The lower shaft 14 is provided with a cylindrical portion 40 journaled in the plate 11 and with an adjacent cylindrical portion 41 to which is keyed a gear 42 in mesh with the gear 17. This gear is held in position against one side of the plate 11 by means of a washer 43 and nut 44 which draws a collar 45 on the shaft against the opposite side of the plate 11. The other end of the shaft 46 is squared and mounted on this squared portion is a dimpling wheel 50 held in position against the collar 45 by means of a washer 51 and a screw bolt 52 as indicated.

The dimpling wheels 23 and 50 are of the same general construction each being of a composite construction comprising a pair of discs 55 and 56 which constitute flanges of a channel the bottom of which is a sleeve member 57 upon which rest the various pin carrying segments 60, 61, and 62 which are held in position by pins 63 supported in segmental peripheral portions of said discs as disclosed more particularly in Fig. 1 which are of the same length as the segments supported between the discs. The segments 60 are provided with radial holes in which are seated pins 64, the upper segment 60 supporting three pins and the lower segment supporting four pins, the first of the pins in the lower segment 60 being spaced at a distance from an abutment plate 65 secured by a screw bolt 66 to said segment, which is less than the distance by which the first pin of the upper segment is spaced from the abutment plate 65 by an amount equal to half of the distance between centers of adjacent pins so that when these segments operate upon an end fitting the pins will be disposed in staggered relation. These segments 60 are intended to operate upon end fittings for cables of $\frac{3}{16}$ of an inch diameter and each of the segments 60 is provided with a groove 70 of approximately the same diameter as the end fitting and each of the abutment plates 65 is provided with a groove 71 of approximately the same diameter as the diameter of the cable to which the fitting is to be applied.

The segments 61 which are shown as operating upon the sleeve member 72 to be secured to a cable 73 of $\frac{1}{8}$ inch diameter are provided with grooves having a diameter equal to that of the sleeve 72 and the end plates or abutments are provided with grooves which have a diameter equal to that of the cable 73 providing abutments for the ends of the sleeve and it is preferable to provide each of these segments with five pins arranged in staggered relation as indicated. The segments 62 have grooves of dimensions to receive a sleeve to be fitted on to a cable $\frac{5}{32}$ of an inch in diameter, and the associated abutments have grooves of $\frac{5}{32}$ of an inch in diameter. It has been found that a series of five pins on each segment is sufficient to secure the sleeve onto a cable of this size. In Fig. 5 I have disclosed an end fitting secured to a cable by means of the segments disclosed in operating position in Fig. 3.

For the purpose of indexing or rotating the fittings so that the dimples will be located in the proper positions circumferentially about the sleeve and staggered longitudinally, I have provided an adapter 80 which for the purpose of preventing bending of the fitting as it is being applied, I have pivoted at 81 in line with the point at which the bending would occur in the absence of the adapter. This adapter is provided with a transversely extending flange 82 provided with an opening through which projects the cylindrical body member 83 of a knurled manipulating indexing member 84. This indexing member is pro-

vided with a pin 85 projecting into an opening 86 in the flange 82 to hold the indexing member against rotation. The flange is provided with three such openings 86 in the case where there are three dimples in each transverse row and six longitudinal rows. The indexing member is held against withdrawal from the flange by means of a pin 87 located so as to permit partial withdrawal in order that the indexing member may be rotated into any one of its three positions. Mounted within the indexing member is a slideable rod 90 keyed to the indexing member for rotation therewith and slideable therein in order that it may follow the movement of the sleeve as it is being secured to the cable. The forward end of this member is provided with a slotted head 91 which may receive the head 92 of the fitting 72, the head of the fitting being secured to the head of the sliding member by means of a threaded pin 93.

In the operation of the machine the sleeve to be connected to the cable and with the end of the cable inserted therein, is connected to the indexing member and its inner end is pushed against the abutments or stops 65 of the appropriate pair of segments which have been previously brought into a position just short of that shown in Figs. 1 and 3. The segments are then rocked by means of the ratchet lever 42 and the sleeve indented by the dimpling pins as is obvious. These segments are rotated until the rear ends of the segments are free of the rear end of the sleeve and permit sidewise removal of the end fitting and cable out of the plane of the segments. Then by means of the ratchet lever the segments are again brought to the position in which their forward ends engage and just prior to this the cable may be moved back into line with the grooves in the segments. The indexing member then is rotated 120° to rotate the sleeve and the sleeve is moved forward against the abutments 65 so that upon the next operation of the ratchet lever dimples will be impressed in the sleeve at 120° angularly from the first rows of dimples. The operation is repeated and the next rows of dimples are made at 120° angularly from the second rows of dimples. This completes the dimpling operation, securely fastening the attachment to the cable. If it is desired to apply a smaller or larger number of longitudinal rows of dimples it is merely necessary to provide a smaller or larger number of openings 66 in the flange 82 equal in number to one-half of the number of longitudinal rows of pins and to space them apart the same number of degrees.

It is obvious that if the apparatus is intended for use only in securing sleeves of the same diameter and lengths to cables of the same diameter, that the segments would all be of the same lengths and the number of pins in the pairs of segments would be the same and that the spaces between the segments would be equal.

In the apparatus disclosed the circumferential length of the segments 60, 61 and 62 and the spaces between the segments, i. e., in back of the respective segments, are respectively $46\frac{1}{2}^\circ$, 55° and 65° , and 55° , 65° and $73\frac{1}{2}^\circ$ as the segments operating on longer diameter sleeves must be rotated farther to free the sleeves so that they may be withdrawn and indexed. The pins in the segments 62 may be of longer diameter than the pins in the other segments and the pins of the respective segments may have diameters of lengths proportionate to the diameters of the sleeves. The centers of the pins may be spaced at twice

the lengths of their diameter. The lengths of the pins preferably decrease as the diameters of sleeves increase to produce the proper depth dimples in varying diameter sleeves.

I have used the term cable in the description and claims in a generic sense for convenience, to cover stranded wire structures comprising a single strand with or without cores and either solid or hollow and also plural stranded structures such as ropes and cables and single elements upon which sleeves can be secured by indenting as described.

While I have disclosed my invention with reference to a specific form of apparatus described in detail, and as modifications thereof will be suggested to those obtaining knowledge of this invention, it is to be understood that I reserve the right to all such changes as fall within the principles of my invention and the scope of the appended claims.

I claim:

1. In a dimpling machine for securing a sleeve upon a cable, comprising rockably mounted opposed members disposed for cooperation with opposite sides of the sleeve, said members being provided with opposed grooves of the same diameter as the sleeve and a series of projections at the bottoms of said grooves.

2. In a dimpling machine for securing a sleeve upon a cable, comprising rockably mounted opposed members disposed for cooperation with opposite sides of the sleeve, said members being provided with opposed grooves of the same diameter as the sleeve and a series of projections at the bottoms of said grooves, the projections on each member being staggered with respect to the projections on the other member.

3. In a dimpling machine for securing a sleeve upon a cable, comprising rockably mounted opposed segments disposed for cooperation with opposite sides of the sleeve, said segments being provided with opposed grooves of the same diameter as the sleeve and a series of projections at the bottoms of said grooves, the projections on each segment being staggered with respect to the projections on the other segment.

4. In a dimpling machine for securing a sleeve upon a cable, comprising rockably mounted opposed segments disposed for cooperation with opposite sides of the sleeve, said segments being provided with opposed grooves of the same diameter as the sleeve, a series of projections at the bottoms of said grooves, the projections on each segment being staggered with respect to the projections on the other segment, and abutment members carried by the forward ends of said segments and provided with grooves of the same diameter as the cable.

5. In a dimpling machine for securing a sleeve upon a cable, comprising rockably mounted opposed segments disposed for cooperation with opposite sides of the sleeve, said segments being provided with opposed grooves of the same diameter as the sleeve, a series of projections at the bottoms of said grooves, the projections on each segment being staggered with respect to the projections on the other segment, and driving connections between said segments.

6. In a dimpling apparatus for securing a sleeve on to a cable, comprising cooperating rockably mounted segments provided with projections adapted to indent opposite sides of the sleeve upon movement of said segments, means for guiding the sleeve during its movement with said

segments and for holding the sleeve against rotation, and means for rotating the sleeve into a different angular position whereby during a second operation of said segments upon the sleeve 5 the sleeve will be indented on opposite sides in positions angularly related to the indentations made by the first operation of said segments.

7. In a dimpling apparatus for securing sleeves of different diameters on cables of different diameters, comprising opposed rockably mounted members each comprising a plurality of spaced segments provided with exterior grooves of different diameters corresponding to the different diameters of the sleeves, and projections at the bottoms of the grooves, the space between the segments on each member and at the rear of the respective segments being of a length proportionate to the length of the sleeve indented by the projections on said segments.

20 8. In a dimpling machine for securing a sleeve upon a cable, a pair of members arranged to operate on opposite sides of the sleeve, each member being provided with holes extending through the member normal to the face opposing the face of the other member, a support for each member, and pins in said holes resting on said support and projecting beyond said opposing face.

9. In a dimpling machine for securing a sleeve upon a cable, a pair of members arranged to operate on opposite sides of the sleeve, a series of projections carried on the opposed faces of said members, means for moving corresponding sections of said members toward each other to indent opposite sides of the sleeve, and means for holding the sleeve against rotation and in different angular positions during successive operations of said members for producing a plurality of pairs of series of indentations.

10. In a dimpling machine for securing a sleeve upon a cable, comprising rockably mounted opposed segments disposed for cooperation with opposite sides of the sleeve, said segments being provided with opposed grooves of the same diameter as the sleeve, a series of projections at the bottoms of said grooves, the projections on each segment being staggered with respect to the projections on the other segment, means for supporting the sleeve for movement with the segments, and a pivot supporting said means in the vicinity in which the projections engage the sleeve.

11. In a dimpling machine, a frame comprising an elongated base, a plate projecting vertically from said base at one side of the longitudinal center line of said base, a pair of shafts journaled in said plate, a pair of cooperating rockable dimpling members carried by said shafts on the side of said plate furthest from an edge of said base, and a manipulating means mounted on one of said shafts on the same side of said plate for operating said dimpling members.

12. In a dimpling machine, a frame comprising an elongated base, a plate projecting vertically from said base at one side of the longitudinal center line of said base, a pair of shafts journaled in said plate, a pair of cooperating rockable dimpling members carried by said shafts on the side of said plate furthest from an edge of said base, a manipulating means mounted on one of said shafts on the same side of said plate for operating said dimpling members, and intermeshing gears on said shaft and located on the opposite side of said plate.

EDMUND P. WILSON.
